INSTRUMENT LIGHTING COVER PANEL

John M. Roper, Washington, D. C., and
Thomas O. Twist, Chevy Chase, Md.

Application March 2, 1950, Serial No. 147,311

13 Claims. (Cl. 240—8.16)

(Granted under Title 35, U. S. Code (1952),
sec. 266)

1

The present invention relates to an instrument lighting system, and more particularly to an instrument lighting system for use in vehicular instrument panels.

It has been the general practice in the prior art to employ a single cover panel hand tailored for all instrument arrangements, the panel being provided with the necessary lighting fixtures. This type of panel has proved to be disadvantageous both in production and actual use. Thus, in production, great care must be taken in tailoring the cutouts to properly fit the individual instruments or the entire panel will be practically useless. Furthermore, a different cover panel is required for each specific arrangement of the instruments on the mounting panel.

In operation, if it is desired to rearrange the instruments on the mounting panel, a new cover panel will be necessary. In addition, continued use of the single cover panel has often resulted in buckling of the panel thereby disrupting the desired distribution of the light and the efficient operation.

The present inventors, in application Serial No. 50,342, filed September 21, 1948, now Patent No. 2,614,205, for Aircraft Instrument Lighting, have proposed one system for obviating the above-mentioned, and other disadvantages of the prior art systems, wherein an individual cover panel is provided for each instrument, this panel having the lighting means for illuminating the dial of its associated instrument mounted thereon.

In operation, the system proposed in the earlier application, although overcoming many of the disadvantages of the prior art, has presented certain problems. Firstly, it has been found that the lamp sockets, which extend upwardly beyond the upper surface of the cover panel of the earlier system have acted as a visual cut-off of the instrument dial. Secondly, due to the fact that the cover panel is mounted on the instrument panel on separate screws, much valuable space has been expended, and difficulty has been experienced in mounting the cover panels over instruments which are in close proximity to each other. In addition, whenever it is desired to remove the instrument from its mounting, it has been necessary to entirely remove the cover panel.

The present invention proposes to eliminate these and other disadvantages by providing a system comprising a mounting base plate which is mounted directly over the instrument mounting means, the base plate being provided with the illuminating means, and a cover panel which is

2

mounted over the base plate by quick detachable mounting means so that the cover panel may be easily and rapidly removed. In addition, a novel arrangement of the illuminating means, and the electrical connections thereto, is provided whereby the lamps occupy a minimum amount of space and provide a maximum amount of illumination for the instrument dial.

Accordingly, an object of the present invention is the provision of an individual instrument lighting cover panel occupying a minimum of space and offering a maximum of illumination of the instrument.

Another object is to provide an individual instrument lighting cover panel which can be secured to the mounting panel by means of the conventional instrument mounting screws.

A further object is to provide an individual instrument lighting cover panel which may be readily removed in a single operation.

Still another object of this invention is the provision of an individual instrument lighting cover panel which in no way interferes with the operator's visibility of the instrument dial.

Other objects and advantages of the invention will hereinafter become more fully apparent from the following detailed description of the annexed drawing, wherein:

Fig. 1 is a front elevational view of a portion of an instrument board illustrating an instrument and a preferred embodiment of the lighting system of the present invention;

Fig. 2 is a front elevational view of the back plate of the present invention with the lamp and lamp connections mounted thereon;

Fig. 3 is a section taken along the line 3—3 of Fig. 1 looking in the directions of the arrows;

Fig. 4 is a sectional view of the lamp and lamp holder of Fig. 2;

Fig. 5 is a plan view, partly in section, of the electrical connector of Fig. 2; and

Fig. 6 is a section taken on the line 6—6 of Fig. 1, with certain parts removed, illustrating the illumination of the instrument dial according to the present invention.

Referring now to the drawing, wherein like reference characters designate like or corresponding parts throughout the several views, there is shown in Fig. 1 a portion 11 of an instrument board having an instrument 12 mounted thereon. Mounted over instrument 12 in a manner to be described below is the lighting system 13 of the present invention, system 13 comprising a cover panel 14 and a back plate 15, shown in Fig. 2.

Referring now to Fig. 2, it is seen that back plate 15 is provided with a pair of lower apertures 16 and a pair of bossed upper apertures 17 through which pass the mounting screws, not shown, of the instrument whereby mounting of the instrument on the instrument board will also simultaneously mount plate 15. Plate 15 is also provided with an internally threaded boss 18 and a pair of integral projecting lugs 19 in order to mount panel 14 over plate 15, the mounting being accomplished by means of screw 21 and a pair of apertures, not shown, in the upper side surface of panel 14.

Mounted on the upper surface of plate 15 by any suitable means 22 is a split electrically insulating body 23 having an electrical sleeve connector 24 passing axially therethrough. As shown in Fig. 5, connector 24 comprises a solid central section 25 having a pin 26 mounted therein to which is connected a lead 27 from one terminal of a power supply, not shown, and a pair of split sleeve end sections 28 in each of which is tightly fitted conducting terminal 29 of lamp socket 31.

As shown in Fig. 4, each lamp socket 31 comprises a cylindrical insulating sleeve portion 32, and a relatively smaller cylindrical sleeve portion 33 joined to portion 32 by means of insulating sleeve 34, all the portions of the insulating sleeve being integral.

Sleeve portion 32 is preferably made of a material translucent to light, such as a material which transmits only red light, although it is clear that sleeve 32 may be made light transparent or of a material which transmits any other color. Socket 31 further comprises a conducting sleeve 35 tightly fitting within sleeve portion 32 and integral with terminal 29, which extends through sleeve portions 33 and 34 and outwardly thereof. The inner surface of connecting sleeve 35 is preferably made light-reflecting, and substantially one-half of the surface thereof positioned in front of lamp 36 is cut away in order to permit the passage of light therethrough.

In order to retain lamp 36 in socket 31, a spring 37 is mounted within a circumferential groove, not designated in sleeve 35, as shown in Fig. 4, a portion of insulating sleeve portion 32 at its outer end being cut away, as shown in Figs. 2 and 4, to permit easy removal of lamp 36. In its operative position, each socket 31 has its terminal 29 extending into section 28 of connector 24, as shown in Fig. 2, the central terminal 38 of lamp 36 abutting against upwardly extending bracket 39, mounted on plate 15, to maintain socket 31 and lamp 36 in fixed position.

By this arrangement of the sockets and lamps, all of the illumination from lamps 36, including that reflected from the back portion of sleeve 35, is directed outwardly through the cut-away portion of sleeve 35 onto the dial 41 and pointer 42 of instrument 12. In addition, it can be seen that lamps 36 and their associated sockets 31 are positioned entirely within the outline of plate 15, thus eliminating the necessity for expending much valuable space. By this arrangement, the instruments may be placed in close proximity on the instrument board, the only limitation being the space occupied by the instrument itself.

It is also apparent that by arranging mounting means 16 and 17 for plate 15 in alignment with the mounting means for instrument 12, as shown in Fig. 2, additional space is saved. Finally, by means of positioning the axes of lamps 36 and sockets 31 parallel to the plane of plate 15, the

possibility of visual cut-off of a portion of instrument dial 41 is entirely eliminated.

Referring now to Fig. 6, which illustrates the light distribution achieved by the system of the present invention, it can be seen that no light rays can emerge from the sides of system 13, due to the presence of upwardly extending flange 43 integrally formed along the outer edges of plate 15 and cooperating downwardly extending integral flange 44 on panel 14. Similarly, the upper surface of panel 14 adjacent each of lamps is provided with a vertical portion 45 and an inclined or bevelled portion 46 in order to prevent any of the light rays from reaching the eyes of the observer directly, and to direct the light rays downwardly toward the instrument dial 41.

In order to prevent any of the direct rays of light from lamps 36 from striking the markings on the peripheral area of dial 41 between ten and two o'clock, opposite sides of the upper portion of plate 15 are provided with projections 48, shown in Fig. 2, which, when the system is assembled, are in the path of such rays so that only direct light rays of angles equal to or less than that of ray 49 reach glass 47, as shown in Fig. 6. Thus, the only rays striking this area of dial 41 are those reflected from flange 46 of panel 14.

To prevent rays of light from being reflected upwardly from the bezel of glass 47 into the eyes of the observer, a flange 51 is provided on the lower surface of plate 15, flange 51 extending into the path of these rays, such as rays 53, as shown in Fig. 6. A flange 52 is provided along the lower surface of panel 14, flange 52 serving to trap any of the light rays directed downwardly toward the lower surface of the instrument and preventing any rays from impinging upon the top of the next instrument.

The distance 54 between flange 46 and projection 48 is critical and is so dimensioned that direct rays from lamps 36 can reach glass 47 at no lower than the approximate center thereof, this limit being indicated by ray 55 in Fig. 6. It has been found that light rays striking glass 47 below this point serve no useful function in lighting dial 41 and pointer 42, but do produce glare by reflection from the surface of glass 46. On the other hand, rays reaching glass 46 at points above the approximate center are refracted through the glass and downwardly toward the bottom of dial 42.

Experimentation has shown that the system of the present invention produces a high degree of uniformity of illumination of the instrument dial and pointer, eliminates substantially all glare, and utilizes most efficiently the space and power available for electrical lighting.

It should be understood, of course, that the foregoing disclosure relates to only a preferred embodiment of the invention and that numerous modifications or alterations may be made therein without departing from the spirit and the scope of the invention as set forth in the appended claims.

The invention described herein may be manufactured and used by or for the Government of the United States of America for governmental purposes without the payment of any royalties thereon or therefor.

What is claimed is:

1. An individual lighting device for each instrument of an instrument board, said device comprising a back plate adapted to fit over the face of the instrument, means for detachably

mounting said plate on the instrument directly over the instrument mounting means, a pair of lamps mounted within the outer confines of and on opposite horizontally aligned upper corners of said plate, respectively, the axis of each of said lamps being substantially parallel to the plane of said plate, a cover panel, means on said plate and said panel for detachably mounting said panel over said plate and lamps, and light-impervious means depending from said plate below said lamps for preventing direct rays of light from said lamps from reaching the peripheral area of the dial of the instrument 60 degrees on each side of a vertical diametrical line through the dial.

2. A device according to claim 1, and light impervious means on said panel cooperating with the last-mentioned means for preventing rays of light from said lamps from striking the glass of the instrument below the center thereof.

3. A device according to claim 2, in which the front surface of said corners and said light impervious means are coplanar.

4. An individual lighting device for each instrument of an instrument board, said device comprising a back plate being apertured to fit over the face of the instrument, means for detachably mounting said plate on the instrument, a pair of lamps mounted on opposite horizontally aligned upper corners of said plate, respectively, said lamps being positioned between the outer confines of said plate and said aperture, the axes of each of said lamps being substantially parallel to the plane of said plate, said plate having integral projections extending into said aperture below each of said lamps for preventing direct rays of light from said lamps from reaching the peripheral area of the dial of the instrument 60 degrees on each side of a vertical diametrical line through the dial, and a cover panel having a vision opening and being detachably mounted on said plate to constitute a frontal shield for said lamps and plate.

5. A device according to claim 4, and a flange depending from said panel and cooperating with said projections for preventing rays of light from said lamps from striking the glass of the instrument below the center thereof.

6. A device according to claim 5 in which the front surface of said corners and said projections are coplanar.

7. An individual lighting device for each instrument of an instrument board, said device comprising a back plate being apertured to fit over the face of the instrument, means for detachably mounting said plate on the instrument, a pair of lamp sockets mounted on opposite horizontally aligned upper corners of said plate, respectively, said sockets being positioned between the outer confines of said plate and said aperture, a lamp mounted in each of said sockets, the axes of each of said sockets being substantially parallel to the plane of said plate, each of said sockets comprising a light-impervious member surrounding said lamp and having a lower portion thereof cut away for emitting rays of light therethrough, said plate having integral projections extending into said aperture below each of said cut away portions for preventing direct rays of light from said lamps from reaching the peripheral area of the dial of the instrument 60 degrees on each side of a vertical diametrical line through the dial, and a cover panel having a vision opening and being detach-

ably mounted on said plate to constitute a frontal shield for said sockets and plate.

8. A device according to claim 1, in which the front surface of said corners and said light-impervious means are coplanar.

9. A device according to claim 4, in which the front surface of said corners and said projections are coplanar.

10. A device according to claim 7 in which the front surface of said corners and said projections are coplanar.

11. An individual lighting device for each instrument of an instrument board, said device comprising a back plate having a front planar

15 surface being apertured to fit over the face of the instrument, the upper portion of said plate aperture being arcuate at least through an angle extending 60 degrees on each side of a vertical diametrical line through the aperture, means

20 for mounting said plate on the instrument, a pair of lamps mounted on opposite horizontally aligned upper corners of said plate, respectively, said lamps being positioned between the outer confines of said plate and said aperture, the axes of each of said lamps being substantially

25 parallel to the plane of said plate, said plate having integral projections depending therefrom and coplanar therewith and extending into said aperture below each of said lamps for preventing

30 direct rays of light from said lamps from reaching the peripheral area of the dial of the instrument 60 degrees on each side of a vertical diametrical line through the dial, and a cover panel having a vision opening and being detachably mounted on said plate to constitute a frontal shield for said lamps and plate.

12. A device according to claim 11, in which a flange depends from said panel and cooperates with said projections for preventing rays of light from said lamps from striking the glass of the instrument below the center thereof.

13. An individual lighting device for each instrument of an instrument board, said device comprising a back plate having a front planar

45 surface being apertured to fit over the face of the instrument, the upper portion of said plate aperture being arcuate at least through an angle extending 60 degrees on each side of a vertical diametrical line through the aperture, means

50 for detachably mounting said plate on the instrument, a pair of lamp sockets mounted on opposite horizontally aligned upper corners of said plate, respectively, said sockets being positioned between the outer confines of said plate

55 and said aperture, a lamp mounted in each of said sockets, the axes of each of said sockets being substantially parallel to the plane of said plate, each of said sockets comprising a light-impervious member surrounding said lamp and having a lower portion thereof cut away for emitting rays of light therethrough, said plate

60 having projections depending therefrom and coplanar therewith and extending into said aperture below each of said cut away portions for preventing direct rays of light from said lamps

65 from reaching the peripheral area of the dial of the instrument 60 degrees on each side of a vertical diametrical line through the dial, and a cover panel having a vision opening and being detachably mounted on said plate to constitute a frontal shield for said sockets and plate.
